UNITED STATES PATENT OFFICE.

ERIC PETERSON, OF LOUGHEED, ALBERTA, CANADA.

POST-CARD-DISPLAY RACK.

1,209,617.

Specification of Letters Patent. Patented Dec. 19, 1916.

Application filed September 17, 1915. Serial No. 51,244.

To all whom it may concern:

Be it known that I, ERIC PETERSON, a subject of the King of England, residing at Lougheed, in the Province of Alberta, Dominion of Canada, have invented certain new and useful Improvements in Post-Card-Display Racks; and I do hereby declare the following to be a full, clear, and exact description of the invention, such as will enable others skilled in the art to which it appertains to make and use the same.

This invention relates to a post card display rack.

An object of the invention resides in the provision of a device which may be suspended from a suitable support and on which a plurality of post cards or similar articles may be arranged in sets so that the members of each set will be disposed in opposite inclined relation to the members of the other set whereby the sets will be turned in opposite direction upon the rising of currents of air through them.

A further object of the invention resides in so constructing the device that a musical sound will be produced upon the rotation of the members carrying the post cards.

A further object of the invention resides in so constructing the device that the sweep which causes the said musical sound may be adjusted with relation to the sound producing members.

With these and other objects in view, such as will appear as my description progresses, my invention comprises the combination and arrangement of parts as set forth in and falling within the scope of the appended claims.

In the drawing: Figure 1 is an elevational view of my device; Fig. 2 is a vertical sectional view; Fig. 3 is a plan view of the upper plate; Fig. 4 is a section on line 4—4 of Fig. 1; Fig. 5 is an enlarged detail of the sweep; Fig. 6 is a section on line 6—6 of Fig. 2; Fig. 7 is a fragmental detail showing the manner of securing the sections of the rim together; and Fig. 8 is a fragmental detail showing the post card holder used with the device.

Referring to the drawings by reference characters wherein like parts are indicated by like characters throughout the several views: In the embodiment of my invention shown in the drawing, I have provided a plate 1 which has an outer row 2 and an inner row 3 of perforations therein and a

plurality of teeth 4 formed on its periphery. Extending through this plate 1 and through a washer 5 on the lower face thereof is a hook 6 by means of which the plate may be secured to a suitable support. An eye 7 is formed on the lower end of the said hook for a purpose which will later appear. Arranged through the perforations 2 and 3 are cords 8 which have eyes 9 on the ends thereof located beneath the plate 1. These cords may however be swung over the edge of the plate between the teeth 4 if desired. Detachably secured to the eyes 9 by means of hooks 10 and cords 11 are tone plates 12 which are arranged in spaced rows, one being beneath the row of holes 2 and the other beneath the row of holes 3. Secured to the eye 7 by means of a hook is a rod 13 which is provided with a hook on its lower end. Engaged with this latter hook by means of an eye 14 is a rod 15, which rod has an eye 16 on its lower end. Secured to the lower end of the rod 15 is a casing 17 in which a plate 18 is mounted. This plate 18 is provided with a groove in which ball bearings 19 are mounted. Resting on these ball bearings is a plate 20 which is secured to a block 21. This block 21 is secured to the under face of a disk 22 to the upper face of which a disk 23 is secured. The rod 15 extends through the plate 20, the block 21 and the disks 22 and 23, the hole through which the rod extends being greater than the diameter of the rod to reduce friction. In order that the disks may be prevented from lateral movement on the rod, I have secured a washer 24 to the upper face of the disk 23 through a hole in which the rod 15 extends which hole is of less diameter than the hole through the disk and of slightly greater diameter than the diameter of the rod. Thus when the disks swing slightly laterally the washer 24 will contact with the rod 15 and the friction produced thereby will be slight. Thus it will be seen that the plate 20, the block 21 and the disks 22 and 23 form a rotary element which is supported by and rotates on the ball bearings mounted on the plate 18 which plate 18 is held stationary with the rod 15.

Extending radially from the upper face of the disk 22 are arms 25 which are located in grooves formed by upwardly extending plates 26. The arms 25 are supported by plates 25'. The inner ends of these arms 25 are upturned and these upturned ends

are located in pockets 27 arranged around the peripheral face of the disk 23. A band 28 encircles this disk 23 and maintains the upturned ends of the arms in their proper 5 positions. The arms will thus be prevented from rotating. These arms are bent downwardly to form a horizontal portion having depressions 28' therein and thence upwardly to form fingers 29. Extending from one to 10 the other of these fingers is a rim which is made up of a plurality of sections having overlapping flanges 30 with which clips 31 are engaged to maintain the sections together. These sections are also provided 15 with loops 32 through which the fingers 29 pass. This rim is provided so that articles may be attached thereto for exhibition purposes. Extending from one to the other of the horizontal portions of the arms 25 are 20 wire rings 33 which are located in the depressions 28' and have downwardly inclined loops 34 for the reception of the post card holders later described. These post card holders which are used with my device 25 consist of plates having a plurality of notches 35 in the edges thereof which plates may be slipped between the sides of the loops 34 until the lower ends of the loops are located in the notches in the plates at 30 which time the plates will be clamped in position and prevented from lateral movement. These plates are provided with clips 36 which extend outwardly from one face of each and which are adapted to engage 35 and maintain a post card in place on the plate. When the plates are arranged in the loops 34 and the post cards are on the plates they are mounted so that the post cards will be visible from beneath. The plates are 40 also provided with lugs 37 which are adapted to engage over the upper edge of the rim so that the post cards may be displayed on the rim also.

Secured to the eye 16 on the lower end 45 of the rod 15 is a rod 38 on the lower end of which a casing 39 is secured in which casing a plate 40 is mounted. A plurality of ball bearings 41 are mounted on this plate 40 and support a plate 42 from the 50 upper face of which a block 43 extends which is secured to the lower face of a disk 44. A similar but smaller disk 45 is secured to the upper face of the disk 44 and a washer 46 is provided to prevent the 55 lateral movement of the disks 44 and 45 in the same manner as described in connection with the washer 24. Secured to and extending outwardly from the disk 44 are arms 47 which are secured to the disk in 60 the same manner and by means similar to those described as securing the arms 25. These arms 47 are provided with depressions 48 in which rings 49 similar to the rings 33 are mounted. Thus it may be seen 65 that the post card holders may be secured

to these rings also. It is to be noted however that the loops on the rings 49 extend in opposite directions to those on the rings 33 so that when the post card holders are mounted on both the rings 33 and 49 and 70 currents of air are forced upwardly from beneath the device the rotary elements on which the arms 25 and 47 are mounted will be rotated in opposite directions. A suitable burner may be placed beneath the device 75 so that the supply of currents of air thereto will be constant.

In order that a series of sounds may be produced as the rotary elements move, I have secured a rod 50 to the disk 23 and have 80 formed a loop 50' in the same which is located within the disk and will prevent the turning of the rod. Rotatably mounted on the outer end of this rod 50 is a sweep which consists of a pair of plates disposed on opposite sides of the rod and secured together, 85 between which plates a brush 51 is mounted which is adapted to engage the lower ends of the tone plates 12. The portion of this sweep which is located below the rod 50 is of 90 greater weight than the portion which is located above the rod so that the sweep is normally held in a vertical position with the brush 51 extending upwardly. Rotatably mounted on the end of this rod 50 is a cylindrical member 52 around which a rubber band 53 extends which also extends around a hook shaped portion 54 of the rod 50 so as to hold the cylindrical member 52 in any of its rotated positions. This cylindrical member 95 is provided with a connecting bar 55 which has a hook on the end thereof extending through an aperture in the sweep. Thus when the member 52 is rotated in either direction the sweep will be swung 100 from its vertical plane and the brush will be lowered or raised so that its engagement with the tone plates 12 will be varied and thus the volume of sound produced 105 also varied.

Thus it will be seen that I have provided a post card display rack which is of such construction that the post cards will be arranged in sets and the rising of currents of air through the sets will cause them to turn 115 in opposite directions. Furthermore I have so constructed the device that it will be easy and inexpensive to manufacture and successful in its operation.

While I have illustrated and described a 120 particular embodiment of my invention, it has merely been for the sake of convenience and I do not wish to be limited to that particular embodiment as it is obvious that numerous changes may be made within the 125 scope of the appended claims.

What I claim is:—

1. In a post card display rack, the combination with a vertically extending rod, of 130 a casing mounted on the rod and having a

bearing plate therein, a disk rotatably mounted on the rod and having a bearing plate thereon, ball bearings interposed between the said bearing plates to permit the 5 disk to rotate freely, the said rod having an eye on the lower end thereof against which the first mentioned plate bears, a second rod secured to the eye at lower end of the first rod, a disk rotatably mounted on the second 10 rod and post card carrying members extending from each of said disks.

2. In a display device, the combination with a disk, of a second disk of less diameter than the first mounted on the upper face of 15 the first disk, pairs of spaced plates arranged on the upper face of the first mentioned disk

and extending radially from its periphery inwardly and terminating in spaced relation to the second mentioned disk, the said second mentioned disk having apertures in its 20 periphery arranged adjacent each pair of plates, arms extending between said plates and having upturned ends in said apertures and a band encircling the second mentioned disk and engaging the upturned ends of the 25 arms.

In testimony whereof, I affix my signature, in the presence of two witnesses.

ERIC PETERSON.
